Primary Examiner — Daniel J Domino*Assistant Examiner* — Samina Vieth(74) *Attorney, Agent, or Firm* — Leydig, Voit & Mayer, Ltd.(57) **CLAIM**

The ornamental design of a radio-frequency antenna, as shown and described.

DESCRIPTION

FIG. 1 is a perspective view of the radio-frequency antenna; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions shown in dotted lines do not form part of the claimed design.

1 Claim, 4 Drawing Sheets(56)
